CLAIM

I claim the ornamental design for a spring toy, as shown and described.

DESCRIPTION

FIG. 1 is a top plan view of the spring toy;

FIG. 2 is a bottom plan view thereof;

FIG. 3 is a side view compacted thereof; and,

FIG. 4 is a side view expanded thereof.

The spring toy is shown with a symbolic break in its length. The appearance of any portion of the article between the break lines forms no part of the claimed design.
